UNITED STATES PATENT OFFICE.

DAVID B. GARY, OF EVERETT, WASHINGTON, ASSIGNOR OF ONE-HALF TO HARRY L. GARY, OF EVERETT, WASHINGTON.

CLAPBOARD-SAWING MACHINE.

Application filed September 7, 1923. Serial No. 661,421.

To all whom it may concern:

Be it known that I, DAVID B. GARY, a citizen of the United States of America, and resident of the city of Everett, in the county 5 of Snohomish and State of Washington, have invented certain new and useful Improvements in Clapboard-Sawing Machines, of which the following is a specification.

10 My invention relates to machines designed for sawing bevel-edged lumber, and particularly bevel-edged lumber of the kind referred to as clapboards.

15 The object of my invention is to provide a simple device which will saw this type of lumber, and one which may be operated so as to distribute the thick and thin sides of the lumber as cut at opposite sides of the cant in any relation desired, thereby to 20 efficiently use up all the lumber in the cant without wastage.

25 The features of my invention upon which I desire to secure a patent will first be described hereinafter, and then be particularly defined in the claim.

The accompanying drawings show my machine in the form of construction which I am now using.

30 Figure 1 is a top or plan view of the machine.

Figure 2 is a transverse sectional elevation, taken substantially upon the plane of the line 2-2 of Figure 1.

35 Figure 3 illustrates the adjustable stop mechanism by which the throw of the tilting lever is controlled.

40 Figure 4 illustrates one of the dogs by which the end of the cant is engaged and supported.

45 As a preliminary step to sawing clapboards, a log is first sawed into cants, the thickness of these cants corresponding with the width of the clapboards. These cants are sawed with reference to the grain of the log so that the clapboards when sawed transversely of the cant will be vertical grained. In sawing the cants out of the log, while two opposite sides would be parallel, the other two sides will not be parallel 50 with each other, but will be somewhat tapered, making the cant of less width at one side than at the other. Such cants are placed in a reciprocating carriage and clapboards sawed therefrom one at a time, the 55 cant being tilted in opposite directions as

may be necessary to suitably cut up the cant.

In the drawings, 1 represents a frame which may be of any suitable character of construction which adapts it to the purpose. This frame has guideways 10 extending lengthwise thereof, in which is slidably mounted a carriage 2 upon which or to which is secured the cant while it is being sawed. A saw 3 is mounted in horizontal position below the path of movement of the carriage so that as the carriage passes over the saw a clapboard will be cut from the lower edge of the cant. To permit of this type of cutting, dogs are employed for 60 engaging the ends of the cants to hold them in place. The carriage 2 is provided with an opening 20 adapted to receive one of the cants. This is of a width somewhat greater than the width of the cant and a 65 length sufficient to accommodate the length of the cants and the dogs by which it is engaged. The cant-receiving opening in the carriage is provided with two depending plates 21, which at their lower edges 70 are inclined towards the center of the opening. The lower edges of these plates are separated a width corresponding as exactly as feasible with the width of the cant used, but not close enough together but that the 75 cant may freely drop between these edges when it is released from the dogs. The dog 4 which is at one end of the carriage, the same being the end which is at the left as it is shown in Figure 1, is mounted 80 upon a cross bar 40 mounted to slide within suitable guideways, or plates as 41 and adjusted in position lengthwise of the cant-receiving opening, by some means by which 85 adjustment may be easily made for varying lengths of cants. Such means as illustrated consist of the threaded bar 42 which is screwed into a member of the carriage and which may be turned as by a 90 crank 43.

95 The other holding dog, 44, is similarly mounted in guideways and is resiliently held in engagement with the other end of the cant C, as by a spring 45 secured by one end to the dog and by the other end 100 to some portion of the carriage. Means are provided by which this latter dog may be automatically withdrawn so as to release the cant at the completion of the 105 return movement of the carriage so that the 110

cant may be dropped upon the tilting table. As illustrated such means consist of the bell crank lever 5 pivoted at 50 upon the carriage and connected by a link 51 with the dog, and a cam stop 52 which is mounted upon the main frame 1 in position to be engaged by one end of the bell crank lever to throw it in the direction necessary to withdraw the dog 44 from engagement with the end of the cant.

Mounted in fixed position beneath the cant-receiving opening and the cant when the carriage is in its fully withdrawn position, is the tilting table. As illustrated this consists of a rod 6 which extends lengthwise of the carriage and is pivoted so as to be rocked upon its axis, and bars 60 secured to said rod 6 and extending transversely thereof to form a support for the cant. Longitudinally-extending rods 61 may be employed, carried by said transverse bar 60 and forming a smoother surface for engagement of the bottom edge of the cant. This tilting table is located at such a level with relation to the level of the saw 3 that a portion of the cant will be cut from the bottom side thereof when the carriage is reciprocated, of such thickness as to form one clapboard. This is shown at the point 30 in Figure 2.

After a clapboard has been sawed from the cant it is desirable that the position of the cant be dropped in the opposite direction so that the thick edge of the clapboard next sawed will be positioned at the opposite side of the cant from that occupied by the clapboard just sawed. To secure this, the tilting table is rocked through a slight angle. The means for doing this as illustrated consist of a lever 62 which is secured to the tilting table and which is engaged by a second lever 63 pivoted by one end upon the frame. This lever is preferably so mounted that it is to a limited extent resilient or may be bent in a direction perpendicular to the plane of its swing. It is also preferably provided with a roller, as 64, which engages with a cam projection 65 carried by the frame so that the swinging of the lever to the full extent of its movement may be assured. After the lever is swung enough to pass over the tip of the cam projection 65, the spring action of the lever 63 pressing the roller 64 against the inclined slope, will tend to throw it up or down as the case may be, until it contacts with the adjustable stop bolts 7, which bolts are mounted in a retaining bar or clip 70. By adjustment of these bolts the amount of throw of the

lever, and therefore the amount of tilt given to the table, may be quickly and very accurately adjusted.

The saw shaft 31 is connected with a shaft 8 at one end of the frame, by means of a quarter turn belt 80. This shaft is connected by means of pulleys 81 and 82, and corresponding belts 83 and 84 with pulleys carried by a shaft 9 located at the opposite end of the frame. This shaft has a tight and a loose pulley for each of the belts 83 and 84. A belt shifter 85 is operated through a bell crank lever 86 and the latter is operated by pins or stops as 87 and 88 carried either by the carriage itself or by an extension bar secured to the carriage. The shaft 9 is connected by the pair of gears 90 with a shaft 91 which has thereon a pinion 92 meshing with a rack bar 93 which is secured to the carriage. The reciprocation of the carriage is therefore secured through the action of the pinion 92 upon the rack bar 93, and the direction of movement is controlled by the reversing mechanism described. The pins 88 and 87, contacting with one arm of the lever 86 as the carriage reaches the limits of its travel in opposite direction reverses the shaft 91, and therefore reverses the direction of travel of the carriage. Any other suitable reversing means may be employed.

The clapboard as cut from the cant drops upon a belt 95 which carries it clear of the machine.

What I claim as my invention is:

A clapboard sawing machine comprising a horizontally mounted saw, a carriage mounted to reciprocate over the saw and having a cant-holding opening, cant holding dogs at the end of said openings, said dogs at one end being yieldingly held against the end of the cant, a stop automatically withdrawing said latter dog at the end of the return stroke of the carriage, a rod journaled to extend under and lengthwise of the cant-holding opening of the carriage when it is withdrawn, bars mounted transversely of the said rod and adapted to receive and support the cant when dropped, a hand operated lever connected with said rod to turn it and having a limited resiliency perpendicular to the plane of its swing, and a cam-like projection engaged by said lever to act with the resiliency of the lever to insure a full throw of the lever.

Signed at Everett, Snohomish County, Washington, this 24th day of August, 1923.

DAVID B. GARY.
